CLAIM

The ornamental design for an illuminated house number, as shown.

DESCRIPTION

FIG. 1 is a front elevational view of an illuminated house number showing my new design with the broken line showing of indicia being for illustrative purposes only and forming no part of the claimed design;

FIG. 2 is a right side elevational view, with the opposite side being a mirror image thereof;

FIG. 3 is a bottom plan view, with the top being a mirror image;

FIG. 4 is a rear elevational view thereof;

FIG. 5 is a cross-sectional view taken on line 5—5 of FIG. 3, and

FIG. 6 is a top, front, and right side perspective view, with the broken line showing of indicia being for illustrative purposes only and forming no part of the claimed design.

FIG.-1

FIG.-2

FIG.-3
